US0D1071354S

(12) **United States Design Patent** (10) **Patent No.:** **US D1,071,354 S**
(45) **Date of Patent:** **** Apr. 15, 2025**

(54) **SAFETY HELMET**

(71) Applicant: **Wenzhou Laolaisi Safety Protection Equipment Co., Ltd.**, Zhejiang (CN)

(72) Inventor: **Long Lin**, Zhejiang (CN)

(73) Assignee: **WENZHOU LAOLAISI SAFETY PROTECTION EQUIPMENT CO., LTD.**, Zhejiang (CN)

(**) Term: **15 Years**

(21) Appl. No.: **29/868,813**

(22) Filed: **Dec. 14, 2022**

(51) LOC (15) Cl. **02-03**

(52) U.S. Cl.

(57) **CLAIM**

The ornamental design for a safety helmet as shown and described.

DESCRIPTION

FIG. 1 is a rear view of a safety helmet, according to the claimed design;

FIG. 2 is a front view of the safety helmet of FIG. 1;

FIG. 3 is a left-side view of the safety helmet of FIG. 1;

FIG. 4 is a right-side of the safety helmet of FIG. 1;

FIG. 5 is a top view of the safety helmet of FIG. 1;

FIG. 6 is a bottom view of the safety helmet of FIG. 1; and,

FIG. 7 is a rear perspective view of the safety helmet of FIG. 1.

The broken lines in the drawings depict portions of the safety helmet that form no part of the claimed design.

1 Claim, 7 Drawing Sheets
